UNITED STATES PATENT OFFICE.

GILMAN W. BROWN, OF WEST NEWBURY, MASSACHUSETTS, ASSIGNOR OF ONE-HALF TO HAYDN BROWN, OF SAME PLACE.

FIRE-ALARM SIGNALING APPARATUS.

SPECIFICATION forming part of Letters Patent No. 544,084, dated August 6, 1895.

Application filed September 1, 1892. Serial No. 444,729. (No model.)

To all whom it may concern:

Be it known that I, GILMAN W. BROWN, of West Newbury, in the county of Essex and State of Massachusetts, have invented certain new and useful Improvements in Fire-Alarm Signaling Apparatus, of which the following is a specification.

This invention has for its object to provide an improved signaling apparatus for use as a part of the improved automatic fire-alarm system shown in Letters Patent No. 463,608, dated November 17, 1891, said patented invention consisting, mainly, in the combination with a main-line circuit and an electromagnet provided with a polarized armature, of a pole-changing thermostat located in the line and adapted to be operated by heat in such manner as to reverse the circuit, and thus cause the electromagnet to so act on the polarized armature as to let off a gong-operating motor and gives an audible signal, said motor being locked by a detent controlled by the polarized armature when the latter is in the position in which it is held by the electromagnet under normal conditions. The apparatus shown in said patent is also organized so that it will give a visual indication of the condition of the line, including a normal condition and the condition caused by a reversal of the current, and will give both a visual and an audible indication of other changes, such as the breakage of the line or the running down of the battery, the visual indication being given in each case by an oscillatory pointer controlled by a galvanometer-coil included in the main circuit, said pointer being held normally at one extreme of its movement by the current through the galvanometer-coil when the system is in its normal condition ready for use, and at the other extreme of its movement when the current is reversed by the action of a thermostat. The pointer assumes by gravitation an intermediate position when the battery is weakened, and another intermediate position when the line breaks. The audible signal is given by any change of position of the polarized armature sufficient to let off the gong-striking mechanism, such change of position being caused by the partial retraction of the armature when the current is weakened by the running down

of the battery and by the complete retraction of the armature which takes place both when the current is reversed by the action of a thermostat and when the line breaks. The 55 said patented apparatus therefore includes two sets of devices—namely: the visual indicator or signal controlled by a galvanometer-coil and the audible signal controlled by an electromagnet and a polarized armature. 60

The present invention has for its object to provide a simpler and more effective signaling apparatus, in which an electromagnet and a polarized armature therefor shall control both the visual and the audible signal. 65

The invention also has for its object to provide an improved form of electromagnet and polarized armature, whereby the lines of force emanating from the poles of the electromagnet are more effectively applied in either attracting or repelling the polarized armature. The invention also has for its object to provide means whereby an attendant may stop the ringing of the gong after an alarm has been given and at the same time display a 70 device indicating that there is a defect in the line, so that it will not be necessary to keep the gong in operation until the line has been repaired. 75

To these ends my invention consists in the 80 several improvements which I will now proceed to describe and claim.

Of the accompanying drawings, forming a part of this specification, Figure 1 represents a front elevation of a fire-alarm signaling apparatus embodying my improvements. Fig. 2 represents a front elevation of parts of the apparatus on a larger scale. Fig. 3 represents a top view of the parts shown in Fig. 2. Fig. 4 represents a section on line 4-4, Fig. 2. 90 Fig. 5 represents a diagram showing the preferred arrangement and manner of connecting the coils of the electromagnet. Fig. 6 represents a front view showing the position of the pointer when in position to indicate that 95 the line is broken. Fig. 7 represents a front view showing the position of the pointer when indicating that a thermostat has been sprung.

The same letters of reference indicate the same parts in all the figures. 100

My improved signaling apparatus or receiving-instrument includes an audible signal,

here shown as an electromechanically-operated gong or bell *a*, (shown in dotted lines in Fig. 1,) a hammer or striker *b*, the arm *b*² of which is pivoted at *b'* to a support within the casing *c*, a motor to oscillate said hammer, and an electrically-controlled let-off mechanism which under normal conditions locks the hammer and is adapted to release the same and permit its operation under the conditions hereinafter described. The motor as here shown comprises a spur-wheel *d*, affixed to a drum *d'*, (shown in dotted lines in Fig. 1,) mounted on a shaft *e*, which is journaled in bearings in the supporting-frame, and a weight *f*, pivoted at *f'* to a pulley *f*³, which is suspended in the bight of a cord *f'*, one end of which is attached to the drum *d'* and the other to an eye *f*², affixed to the casing *c*. The gravitating force of the weight tends to rotate the spur-wheel *d* in the direction indicated by the arrow in Fig. 1. The teeth of the spur-wheel co-operate with pawls *g* *g'*, which are pivoted to the hammer-arm, said teeth and pawls being formed and arranged as in gong-striking mechanisms already well known to cause the rotation of the wheel *d* to impart an oscillating movement to the hammer *b*.

The hammer is locked and released by the action of an electromagnet on a polarized armature, but said electromagnet and armature instead of controlling only the hammer or striker, as in my former patent, are constructed to also control the pointer or visual signal *h*, which co-operates with the graduated scale-plate *i* in indicating the different conditions that may exist in the system. The electromagnet preferably comprises four coils or spools *i* *i* and *i'* *i'*, arranged horizontally and arranged about a common center, the coils being connected as indicated in Fig. 5, so that the coils *i* *i* are of one polarity and the coils *i'* *i'* of opposite polarity. The cores of said magnets have extended pole-pieces *i*², each of which is provided with a slot *i*³.

j represents the polarized armature, which is made with a series of arms *j'* corresponding in number with the coils of the electromagnet—that is to say, there is one arm *j'* for each magnet-coil. The armature is made of hardened steel and is a permanent multipolar magnet, two of its arms being positive poles and the other two negative poles, the positive and negative poles alternating, as shown in Fig. 2, where the positive poles are indicated by the sign + and the negative poles by the sign -.

The armature *j* is affixed to a shaft or stud *j*², which is journaled to turn in bearings in a fixed support, the pointer *h* being affixed to said shaft.

*j*³ represents a collar affixed to the shaft *j*² and provided in its periphery with two recesses *j*⁴ *j*⁴. Said collar constitutes a part of the let-off mechanism, which includes, also, a lever *k*, pivoted at *k'* to a fixed support and provided with an arm *k*², arranged to bear on a finger *b*³ on the hammer-arm, (and thus lock

the hammer,) and a weighted arm *k*³, pivoted at *k*⁴ to the upper end of the lever *k*. Said arm *k*³ has at one end a tooth or projection *k*⁵, (preferably provided with a small antifriction-roller, as shown in Fig. 2,) which is formed to engage one of the recesses in the collar *j*³, the weight *k*⁶ on the opposite end of the arm *k*³ being arranged to press the projection *k*⁵ upwardly against the collar *j*³ when the parts are in the position shown in Fig. 2. The arm *k*³ is provided with a tooth *k*⁷, which when the projection *k*⁵ is in one of the recesses *j*⁴ engages a fixed stop *k*⁸ on the supporting-frame, thus locking the arm *k*³, lever *k*, and hammer *b*. The arrangement is such that the hammer is locked as last described only when the armature *j*, pointer *h*, and collar *j*³ are in the position in which they are held by the electromagnet when the system is in its normal condition and in working order, the direction of the current being then such that the attraction of the arms of the polarized armature by the poles of the electromagnet holds the armature in the position shown in Figs. 1 and 2, the pointer *h* being over the mark "O. K." on the plate *i* and the projection *k*⁵ in the first recess *j*⁴.

The main circuit includes a series of pole-changing thermostats located at suitable points in the building or plant protected by the system, each thermostat having two sets of pole-changing arms, one set consisting of conducting-springs held in tension by fusible solder and in position to conduct the current in one direction, while the pole-changing arms of the other set are connected to said springs and although normally not included in the line-circuit are included therein by the operation of the springs to reverse the line-current when said springs are released, so that the rupture by heat of the fusible solder holding the springs in tension will cause a reversal of the current in the manner fully described in Patent No. 463,608, above referred to.

When the current is reversed as last described, the reversal of the polarity of the poles of the electromagnet causes each pole to repel the arm of the armature previously attracted by it and attract the next arm, so that the armature and pointer will be moved to the position shown in dotted lines in Fig. 2. This movement will cause the collar *j*³ to displace the arm *k*³ and release the hammer, and at the same time cause the pointer *h* to point to the word "Fire" on the plate *i*.

In case the line breaks the electromagnet becomes demagnetized and releases the armature, so that the pointer *h* moves by gravitation to a vertical position, as shown in Fig. 6, and points to the words "Line broken" on the plate *i*, the collar *j*³ being at the same time moved sufficiently to release the hammer or striker.

The armature and pointer are held in the position to indicate "O. K." and prevent the operation of the hammer, wholly by the force of the current. Hence any weakening of the lat-

ter permits the pointer to move by gravitation toward a vertical position. In case the current becomes sufficiently weakened by the running down of the battery to permit the 5 first recess j^4 to pass by the projection k^5 , the hammer is released and at the same time the pointer points to the words "Battery run down" on the plate i . It will be seen, therefore, that an audible and a visual signal or indication are given in case of each of the events 10 above described.

As it is not desirable that the gong should continue to ring indefinitely after it has been released by the breakage of the line, I provide 15 a device whereby the operator may restore the projection k^5 to engagement with a recess in the collar j^3 , thus locking the hammer and at the same time displaying a sign indicating that the line is not operative. Said 20 device comprises a plate o , which bears the word "Disconnected," and is pivoted at o^1 to a support within the casing. Said plate has a pin or stud o^2 , which is arranged to act on a projection or cam k^6 on the lever k .

25 o^3 represents a rod pivoted at o^4 to an offset ear on the plate o and extending through the casing c , its outer end having a knob or handle. When the armature has been released by the breaking of the line, the collar j^3 stands 30 in such position that its second or right-hand recess j^4 is in position to receive the projection k^5 , when the arm k^3 is moved to position to engage its tooth k^7 with the fixed tooth k^8 . Normally the plate o stands in the vertical 35 position shown by full lines in Fig. 1 and is concealed by an opaque part of the door of the casing. When an alarm has been given by the breaking of the line, the operator may stop the operation of the gong by pulling out 40 the rod o^3 , thus causing the plate o to swing to the horizontal position shown by dotted lines in Fig. 1, so that it can be seen through the glass of the door. This movement causes the pin o^2 to act on the cam or projection k^6

45 in such manner as to throw the lever k into its hammer-arresting position and engage the projection k^5 with the second recess j^4 . The gong is therefore silenced, but the plate o remains in position to show that the line is inoperative. After the line has been repaired 50 the hammer will be released by the movement of the armature and pointer back to the "O. K." position. The operator then seeing that the line is operative pushes in the rod o^3 , thus 55 raising the plate o to its concealed position and causing the pin o^2 to again throw the lever k to its hammer-locking position and engage the projection k^5 with the first recess j^4 , as shown in Fig. 2. It will be seen, therefore, 60 that the same electromagnet controls both the audible signal and the visual signal, so that the apparatus is materially simplified by the employment of the multiple-pole electromagnet and the multiple-pole polarized armature 65 adapted to swing or rotate on a horizontal axis. The electromagnet and armature thus organized are particularly adapted to control

both a gong-striking mechanism and a visual signal or pointer, because the armature moves in a plane that is parallel with the attracting- 70 surfaces of the poles of the electromagnet and is always more completely under the control of the lines of force emanating from said poles than would be the case if the armature were movable in a direction substantially at 75 right angles with the attracting-surfaces of the poles of the electromagnet, as in the ordinary arrangement of an electromagnet and its armature.

It is well known that the force exerted by 80 an ordinary electromagnet, such as that shown in my former patent, on its armature, decreases very rapidly as the armature recedes from the poles of the magnet, so that while the force is comparatively great when the 85 armature is in contact with or in very close proximity to the poles, it is comparatively weak when the armature is retracted, and is not therefore adapted to give the armature a sufficiently strong and quick initial movement 90 when the current is reversed to operate the two signals with the desired certainty and promptness. My improved construction and arrangement of the electromagnet and its polarized armature obviate this objection, the 95 armature being at no part of its movement sufficiently removed from the acting-surfaces of the poles of the electromagnet to materially deprive the lines of force of the desired control over the armature. 100

I prefer to bevel the surfaces of the arms of the armature j at their edges, as shown in Figs. 2 and 3, the beveled faces being arranged to cause a sufficient variation in the force exerted on the armature by the poles of the 105 electromagnet to give the armature a longer excursion than it would have if its sides were not thus beveled, there being a slight increase of force during the movement of each arm into the slot i^3 that receives it until the beveled portion has entered the slot. 110

p represents a shield affixed to the casing c in position to cover the weight f , when the latter is in its highest position. When the weight descends in operating the gong, it 115 emerges from behind the shield and becomes exposed to view, thus making it apparent that an alarm has been given, so that the fact that the line is disconnected and that the gong-striking mechanism is in a run-down or inoperative condition will be conspicuously indicated. I prefer to mark the word "Alarm" 120 on the weight, as indicated in dotted lines in Fig. 1. The line wires $x x'$, which are connected with the coils of the electromagnet in 125 the manner indicated in Fig. 5, enter the apparatus through a switch y and a lightning-arrester z , which are or may be of any suitable and well-known construction.

I do not limit myself to the particular devices here shown, whereby the hammer is locked and released by movements of the polarized armature, as said devices may be variously modified without departing from the 130

spirit of my invention; neither do I limit myself to the use of the slots in the poles of the electromagnet, although I prefer the same because they increase the areas of the attracting-
5 surfaces of said poles.

The combination of a polarized armature, mounted to rotate or oscillate in a plane parallel with the acting surfaces of the poles of the electromagnet, with a visual signal and
10 the let-off mechanism of an audible signal, both controlled by said armature, is new, so far as I am aware. Hence I do not limit myself so far as the form and construction of the electromagnet and armature are concerned,
15 as any form and construction which will produce the described result, the armature being adapted to move as described relatively to the acting surfaces of the poles of the electromagnet, is intended by me to be within the
20 scope of my claims.

I claim—

1. A multipolar electro magnet having its poles arranged around a common center and each provided with a slot the sides of which
25 constitute the acting surfaces of the poles, combined with a multipolar polarized armature mounted to rotate in a plane substantially parallel with said surfaces, and between the sides of said slots, as set forth.

30 2. A multipolar electro magnet having slotted poles, the sides of the slots constituting the acting surfaces of the poles, combined with a multipolar polarized armature mounted to rotate or oscillate in a plane substantially
35 parallel with said surface and provided with beveled sides, as set forth.

3. The combination of an electro magnet, a polarized armature mounted to rotate or oscillate in a plane substantially parallel with
40 the acting surfaces of the poles of the electro magnet, a pointer or visual signal affixed to said armature, an audible signal or gong having a striking mechanism, and a let off mechanism controlled by said armature, as set
45 forth.

4. The combination of an electro magnet, a polarized armature mounted to rotate or oscillate in a plane substantially parallel with the acting surfaces of the poles of the electro
50 magnet, an audible signal or gong having a striking mechanism, and a let off mechanism comprising first a pivoted lever having an arm or detent adapted to arrest the striking mechanism, secondly a notched or recessed collar
55 affixed to the polarized armature, and thirdly

a latch or weighted arm pivoted to said lever and adapted to engage a tooth on said weighted arm and thus lock the lever and the striking mechanism when the said arm is engaged with the recessed collar, said arm being displaced by a movement of the armature and collar, as set forth.

5. The combination of an electro magnet, a polarized armature mounted to move in a plane substantially parallel with the acting
65 surfaces of the poles of said magnet, a gong or audible signal having a striking mechanism, a let off mechanism for said striking mechanism controlled by said armature and adapted to be operated to release the striking
70 mechanism by a movement of the armature from its normal position, and a combined indicator and resetting device adapted to restore the let off mechanism to its hammer locking position, as set forth.

75 6. The combination of an electro magnet, a polarized armature mounted to rotate or oscillate in a plane substantially parallel with the acting surfaces of the poles of the electro magnet, an audible signal or gong having a
80 striking mechanism, a let off mechanism comprising first a pivoted lever, adapted to arrest the striking mechanism, secondly a collar affixed to the armature and provided with two recesses in its periphery, and thirdly a
85 latch or weighted arm pivoted to the lever and adapted to engage one of said notches, a fixed tooth or detent arranged to engage a tooth on said weighted arm when the latter is engaged with one of said notches, and a
90 pivoted plate or indicator within the casing, provided with an operating rod and with a pin or projection arranged to co-operate with cam or projection on said lever in resetting the let off mechanism, as set forth.

95 7. The combination of a polarized armature, a pointer or visual signal connected therewith and adapted to be moved by changes of position of the polarized armature, an electro-mechanical gong, and a let off mechanism which is released by a movement of the said armature.

In testimony whereof I have signed my name to this specification, in the presence of two subscribing witnesses, this 9th day of August, A. D. 1892.
